UNITED STATES PATENT OFFICE

FRED E. EDGREN, OF CHICAGO, ILLINOIS

STRAIGHTEDGE FOR WALL-PAPER TRIMMERS

Application filed January 2, 1930. Serial No. 417,997.

My invention relates to a straightedge of the type more particularly intended for use in connection with wall paper trimmers and has for its object the provision of a straightedge which will not shrink or warp and therefore a straightedge made entirely of metal.

The invention also has for its object the provision of a straightedge which will have the required strength and which at the same time will not be of too great weight; and which may be easily manufactured and therefore not be of prohibitive cost.

Furthermore, the invention also contemplates a straightedge whereby proper holding of the paper or material to be trimmed will be had throughout the length of the straightedge.

The objects and advantages above outlined, as well as other advantages inherent in the invention, will all be readily comprehended from the following detailed description of the accompanying drawing, wherein:

Figure 1 is a perspective view of my improved straightedge, with an intermediate portion broken away to thereby show the general construction.

Figure 2 is a cross-sectional view, taken substantially along the line 2—2 of Figure 1, as viewed by the arrows.

Figure 3 is a cross sectional view showing a modification of the invention.

In the particular exemplification of the invention, as shown in Figures 1 and 2, the main body 10 of the straightedge is made from a blank of comparatively thin sheet metal of the required length (straightedges of this character being usually of six, seven and eight feet length) and width; the longitudinal edges whereof are then bent downwardly so as to provide a main channel member of required depth to permit use of the usual trimming tools at present employed wherein the cutting disk or knife carrying shoe or member has a limited degree of downward movement; the channeling of the member 10 at the same time providing it with the requisite strength against pressure.

The outer edge of the device may merely be bent at right angles to the main body portion, as shown at 11; while the inner or cutting

side of the straightedge preferably has the longitudinal edge bent downwardly at right angles to the main body portion to provide the intermediate portion or leg 12, with the lower edge or portion then bent backwardly or inwardly to provide the horizontally disposed leg or portion 13 which extends parallel with the upper or main body portion 10 of the straightedge. 55

In order to give the device a more finished appearance and at the same time add to its strength, I provide a metallic filler member 14, which is preferably made from a blank or sheet of aluminum, which is given the inverted channel formation shown in Figure 2, so that the base 15 of the channel may extend flush with the lower face of the main body 10; and the legs or sides of the filler channel 14 are then bent laterally outward, as shown at 16, 17, so as to extend substantially to the depending longitudinal sides 11 and 12 of the main body 10; the lateral legs or portions 16 and 17 being preferably of some width so as to provide comparatively wide bearing surfaces. In order to further strengthen or reenforce the device, the lateral leg 16 of the aluminum filler member 14 is shown with the outer longitudinal edge bent upwardly at right angles with the lateral leg 16, as shown at 18 in Figure 2, so as to extend flush with the inner face of flange 11 of the body member 10, with its longitudinal edge preferably arranged in bearing relation with the lower surface of the body member 10, as shown to the right in Figure 2. 70 75 80 85

The intermediate portion 15 of the filler member 14 is then secured to the main body member 10 in a suitable manner, as for example by rivets 19 driven through the members at suitable distances apart throughout the length of the device and preferably along the longitudinal center thereof as shown. 90

In order to give the device a more finished appearance, while at the same time adding strength thereto, I prefer to make the top portion of the main body member 10 slightly longer than the predetermined length of the finished straightedge in order that these ends of the top portion may then be bent downwardly, as shown at 20 in Figure 1, so as to 100

cover the ends of the filler member 14; the downwardly bent ends 20 being preferably made to terminate slightly short of the main longitudinal edges of the device in order that the longitudinal edges may engage and hold the paper, or other material being trimmed, throughout the entire length of the straight-edge.

The inner or operating side of the device is then provided with the straightedge track channel or member 21, which is usually made of a non-rusting metal having sufficient strength, such as suitable brass. The track member 21 is in the nature of a channel bar of width greater than the thickness of the body 10 in order that it may be placed flush along the edge of the device with the lower leg 22 of the track channel arranged flush with the bottom of the device; while the upper leg 23, is preferably of somewhat greater width than the lower leg 22 so as to provide a proper track for the usual gauge portion or guide of the cutting or paper trimming tool.

The width of the channel 21 is such that the upper horizontally disposed leg 23 will extend parallel with the body 10 of the device but in slight spaced relation therewith, as shown in Figure 2, so that the trimmer guide may fit beneath the flange or leg 23.

In a device of this character it is essential to provide an absolutely smooth surface along the inner longitudinal or operating side of the straightedge so as not to interfere with the cutting blade which extends flush with the vertical side of the track channel 21. For that reason, the track channel 21 is provided with the bottom flange or leg 22 in order to permit the use of small screws, as at 24, for securing the track channel in place. A sufficient number of these screws are used throughout the length of the device; and the heads of the screws are preferably countersunk as shown so as to provide a smooth paper engaging bottom surface. The use of screws along the vertical portion of the track channel 21 is objectionable, because they are apt to slightly protrude or become loosened and therefore come into contact with the cutting disc of the trimmer, causing damage to the cutting edge and necessitating frequent sharpening of the cutting disc. With the track channel arranged as shown and with the fastening screws located as described, all danger of contact between the cutting disc and the screws or burrs on the vertical side of the track channel is eliminated.

In assembling the device, the laterally disposed leg 17 of the filler member 14 has been shown arranged between the flange 13 of the body member 10 and the flange 22 of the track channel, but it will be understood that the lateral flange 17 of the filler member 14 may be arranged to lap the inner or top surface of the flange 13, providing thelapping flanges 13 and 17 provide a greater

amount or thickness of metal for the attaching screws 24 and therefore ensure greater security.

In Figure 3 I illustrate a modification of the invention of a somewhat cheaper construction because of the elimination of the filler element 14.

In this form of the device, the body member 25, like the body member 10, is made from a blank of sheet metal of proper length and width, to permit the longitudinal sides to be bent downwardly at right angles to form the flanges 26, 27; the lower edges whereof are then bent inwardly at right angles, as shown at 28, 29. By bending the lower edge inwardly, as shown at 28 in Figure 3, the device is provided with a paper engaging surface of sufficient width to firmly hold the paper or material being trimmed; while at the same time the lateral flange 29 provides a surface to receive the screws 24 whereby the track channel 21 is secured in place at points where there can be no contact with the cutting disc.

In construction, the outer longitudinal side 11 or 26 of the straightedge is preferably made of vertical width slightly less than the vertical width at the forward or inner longitudinal or track side, thus giving the device a slight tilt or inclination so as to ensure sufficient pressure on the paper or material by the longitudinal side 11 or 26 during trimming operations; the main metal body is given a suitable enamel finish so as to prevent corrosion; the enamel coating being applied before the track channel 21 is applied.

With my invention, a non-warping, non-shrinking straightedge is provided which is not subject to climatic conditions as is the case with straightedges constructed of wood; while at the same time a straightedge is provided wherein the track channel fastening means are located on the underside of the device where contact with the cutting disc is impossible, thus presenting a smooth unbroken surface on the forward vertical side of the track channel adjacent to which the cutting disc travels.

I have shown what I believe to be the preferred embodiments of my invention; having described the same in terms employed merely as terms of description and not as terms of limitation, as structural modifications are possible and may be made without, however, departing from the spirit of my invention.

What I claim is:

1. A wall paper trimmer's straightedge comprising an elongated main body of sheet metal, the longitudinal sides whereof are bent downwardly at right angles; and a metal track channel member arranged flush with said forward side, with the sides of the track channel member disposed inwardly of the main body, one side of the track channel

member being immovably secured to the bottom of the body member, while the other side of the track channel member is disposed in parallel spaced relation with the upper surface of the main body.

5. A straightedge for wall paper trimmers comprising a metallic body member, the longitudinal edges whereof are bent downwardly to provide supporting legs, with the forward leg being provided at the bottom with a lateral flange disposed inwardly; a metallic channel track member whose intermediate portion is arranged parallel and flush with the forward side of the body member, with the upper flange of the channel member disposed inwardly parallel and in spaced relation with the top surface of the body member, while the bottom flange of the channel member is arranged parallel with the laterally disposed flange of the body member; and means whereby said last mentioned flanges are secured together.

3. A straightedge for wall paper trimmers comprising a metallic body member whose longitudinal sides are bent downwardly at right angles to provide supporting legs; a metallic filler member of channel formation having its base arranged flush with the lower surface of the body member, while the lower sides of the channel are flanged laterally and said flanges disposed toward the opposite downwardly disposed sides of the body member; means whereby the base of the filler member is secured to the body member; a metallic track channel disposed flush with the forward side of the body member, with the upper flange of the track channel disposed inwardly parallel and in spaced relation with the top of the body member while the lower flange is arranged in lapping relation with a laterally disposed flange of the filler member; and means whereby the last mentioned flanges are secured together.

4. A straightedge for wall paper trimmers comprising a body member made of an elongated sheet of metal, the longitudinal sides whereof are bent downwardly at right angles to provide supporting legs, with the leg at the forward side terminating in an inwardly disposed flange; a metallic channel track member whose intermediate portion is arranged parallel and flush with the forward side of the body member, with the top flange of the track member disposed inwardly parallel and in spaced relation with the top of the body member, while the bottom flange is arranged inwardly parallel with the flange of the body member; and means disposed through said last mentioned flanges on the bottom of the straightedge whereby the track member is removably secured in place.

5. A straightedge for wall paper trimmers comprising a body member composed of an elongated sheet of metal whose longitudinal sides are bent downwardly at right angles to

provide supporting legs, the leg at the forward side terminating in an inwardly disposed flange; a metallic channel member whose base is arranged flush with the lower surface of the body member and is secured thereto, while the sides of said channel member terminate in lateral flanges disposed toward the opposite side legs of the body member, with the one flange arranged in lapping relation with the flange at the lower forward side of the body member; the ends of the body member being bent downwardly across the ends of the channel member; a metallic channel track member arranged flush with the forward side of the body member while the flanges of said track member are disposed inwardly, with the top flange parallel and spaced above the body member and the lower flange lapping the bottom flange of the body member and the lateral flange of the channel member; and means disposed through the three last mentioned flanges for removably securing the track member in place.
